Res. 450

Samuel M. Carpenter of Erie Penn
Letters Patent No 450 Dated March 30th 1852

The Schedule referred to in these Letters Patent, and making part of the same

To all whom it may concern.

Be it known that I Samuel M. Carpenter of Erie in the County of Erie, and State of Pennsylvania have invented or produced a new design or figure to be cast upon a new looking Stove to be known by the name of the "Keystone" and I do hereby declare that the following is a full & exact description of the same.

Upon the front end plate on each side of the double doors is placed an ornament, called a Harp Scroll with Fan top marked in drawing No 1. Upon the front double door & upon the large end Fire Door is affixed an ornament resembling a fleur de lis Mark² No 5.

Between the two fire chambers is placed on each side of the stove a vine marked No 3. and upon the central section of the elevated oven, there exists two rows of Birds of nine each marked No 2. Around the margin of the hearth & forming the mouldings round the exterior projection of all the fire doors, is the top of a series of Gothic Miniature arches Mark³ No 4. And through the centre of the large oven door stands the appearance of a stone wedge to represent the keystone of the arch.

Upon the general arrangement of said ornaments upon said stove as an original design your petitioner asks a patent under the provisions of law in such case made & provided.
